UNITED STATES PATENT OFFICE.

CHARLES W. DAUGHS, OF PORTLAND, OREGON, ASSIGNOR TO DAUGHS SHIP CRANE COMPANY, A CORPORATION OF OREGON.

ROTARY PIPE-CONNECTING DEVICE.

Application filed August 12, 1924. Serial No. 731,563.

This invention relates to a rotary pipe connection for steam engines.

The general object of the invention is to provide an improved connection which will enable a rotating steam engine to remain in constant communication with a fixed source of steam supply.

One of the specific objects of the invention is to provide a rotary connection device which will enable a crane engine to be continuously operated from a fixed boiler while the crane is sluing back and forth.

Another object of the invention is to provide a rotary connecting device including a fixed base member and a movable valve member with means whereby the fixed member is in communication with the boiler and the movable member is in communication with the cylinders of a steam engine.

Other objects of the invention will be apparent from the following description taken in connection with the accompanying drawings wherein Fig. 1 is an elevation of a crane showing my invention applied thereto; Fig. 2 is a section on line 2—2, Fig. 3; Fig. 3 is a section on line 3—3, Fig. 2; Fig. 4 is an elevation of a connecting member; Fig. 5 is a central section through the connecting member; Fig. 6 is a bottom plan view of the connecting member and Fig. 7 is a sectional detail showing the packing.

Referring to the drawing by reference characters, I have indicated my structure generally at 10. This new structure is shown in the accompanying drawing as associated with a crane 11 which comprises standards 12, rack and roller path 14, base plate 15 and engine 16. The crane is provided with a boom 17, with a mast 18, and with boom, and load hoist cables 19 and 20. Cranes of this character are adapted to rotate about the central mast and to carry merchandise and other articles from place to place.

The details of the crane and its mountings are shown and described in my co-pending applications. In the present application I describe my novel mechanism in use with a crane but it will be understood that it is equally well adapted for use for other purposes.

In order that a continuous flow of steam may be furnished from a boiler to the crane engine while the crane is sluing back and

forth, I provide the improved rotary steam connection 10. This valve comprises a body portion 25 which is shown as provided with an eccentric recess 26 therein. Within this eccentric recess I provide a member 27 which is adapted to rotate freely in the recess 26. The inner wall of the body 25 is provided with piston ring grooves 30 for the reception of piston rings 31 while the member 27 is provided with piston rings 33 fitted therein, in piston ring grooves 32.

The grooves in the piston rings are so placed that the outward thrust of the rings is against the outside wall on both the inside and the outside portions of the member 27. In order to secure the member 27 in place, I provide a closure 35. This closure 35 in reality comprises a pair of annular members having a space 35' between them. The member 27 is provided with rabbeted portions 37, 38 to receive steam packing 39. The closures 35 are provided with packing rings 40 which engage the packing 39 to force the latter to place. The closures 35 may be held in place by bolts 41. The packing rings 40 are shown as coacting with threaded members 42 which serve to adjust the packing rings downwardly against the packing 39 to insure a tight joint.

The member 27 is provided with an annular hollow cavity 45 which extends entirely around the valve. This cavity is shown as communicating with a fixed steam pipe 46 shown as arranged in the stationary body 25. In order that the engine 16 may be continuously in communication with the chamber 45 and consequently with the steam line 46 to a boiler, I provide a coupling member shown at 50. This coupling member serves to connect the rotary member 27 with a steam line 48 which is in communication with the cylinders 49 of the engine 16 as shown in Fig. 1.

The coupling member 50 comprises a body part having a passage 51 therethrough. The body part has an annular flange 52 at the top thereof and the portion of the passage 51 adjacent the flange is round. At the lower end a flange 53 is provided. This latter flange is arcuate at its inner and outer edges 54 and 55 to fit within the recess 35. The portion of the passage 51 adjacent the lower flange 53 takes the shape of a curved narrow elongated slot.

As the engine moves back and forth the engine and means to provide a fluid tight joint member 27 rotates within the body 25 and continuously supplies steam to the engine 16. In order that the rotational thrust may 5 be taken from the steam connection 48 I provide a pair of brackets 60 as shown in Fig. 4. These brackets 60 are preferably arranged on diametrically opposed sides of the valve 27. One end of each bracket is secured to 10 the member 27 while the other end of the bracket may be secured to a fastening member 61 in the base plate 15 (shown in dotted lines in Fig. 1) thus taking off the strain from the steam connection when the crane 15 slues back and forth.

Having thus described my invention, I claim:

1. In a steam pipe connecting device, the combination with a fixed mast, of supports 20 about said mast, an annular body member mounted on said supports and surrounding said mast, and having a cavity therein, an annular member rotatably mounted in said cavity to provide a steam cavity, a steam line 25 leading to said first mentioned cavity, a second steam line fixed on said annular member and mounted to rotate therewith, said second steam line being adapted to be secured to a steam engine and means to provide a fluid-tight joint between said members.

2. In a steam pipe connecting device, the combination with a fixed mast, of supports 35 about said mast, an annular body member surrounding said mast and having an upwardly facing cavity therein, an annular member mounted to rotate in said cavity, said member having a downwardly facing cavity therein, a steam line leading to said first mentioned cavity, a second steam line 40 fixed on said annular member and mounted to rotate therewith, said second steam line being adapted to be secured to a steam en-

45
between said members.

3. A device for connecting a movable steam engine with a relatively stationary source of steam, said device comprising a fixed annular body member having an upwardly facing cavity therein, an annular member mounted to rotate in said cavity, said member having a downwardly facing cavity therein, a steam line leading to said first mentioned cavity, a second steam line 50 fixed on said annular member and mounted to rotate therewith, said second steam line being adapted to be secured to a steam engine, packing rings engaging said body member and said annular member to provide a fluid tight joint, a cavity between said member and said body, packing in said cavity, and means mounted on said body and adapted to engage said member to hold the latter in place.

4. In a steam pipe connecting device, a 55 mast, a base, a rotary member mounted to rotate on said base, a steam engine mounted on said member, a separately mounted source of steam and means to afford a continuous flow of steam from the source to the steam 60 engine while the member is rotating, said means including a fixed body member surrounding said mast, a member engaging said fixed member to rotate thereon, a steam cavity between said members, a steam conduit 65 passing through the fixed member and connected to the source of steam, a second steam conduit engaging said rotary member and mounted to rotate therewith, said second steam line being adapted to supply steam to 70 the engine, and means to provide a fluid tight joint, between said fixed member and said rotary member.

75
In testimony whereof, I hereunto affix my signature.

CHARLES W. DAUGHS.
